UNITED STATES PATENT OFFICE.

JOSEPH N. CLOUSE, OF ST. LOUIS, MISSOURI, ASSIGNOR TO THE PATENT HEADING COMPANY, OF TOLEDO, OHIO.

FASTENER FOR BARREL-HEADS.

949,975.

Specification of Letters Patent. Patented Feb. 22, 1910.

Application filed September 8, 1908. Serial No. 451,983.

To all whom it may concern:

Be it known that I, JOSEPH N. CLOUSE, a citizen of the United States, residing at St. Louis, in the State of Missouri, have invented 5 certain new and useful Improvements in Fasteners for Barrel-Heads; and I do declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention relates to improvements in fasteners for barrel heads such as are designed to be used for packing pork in to cure it, also pickles, and sauerkraut. And the object of my invention is to do away with the 20 labor and expense of heading up and unheading the barrels every time that the packer is desirous of examining the contents of the barrels, and besides it is almost impossible to get the barrels tight again after 25 they are once used and opened in that way, by taking off some of the hoops; and again, the saving of the barrels is certainly a great 30 object. I attain these objects by the mechanism illustrated in the accompanying drawing, in which—

Figure 1 is a face view of the head complete, with the removable head portion locked into the outer rim. Fig. 2 is a vertical center cut section of the head complete 35 taken on the line $x-x$ Fig. 1. Fig. 3 is a face view of the removable part of the head taken out separate showing the bolts drawn from the outer rim. Fig. 4 is an enlarged detail group of perspective views of the several parts forming the central movement of 40 the device. Fig. 5 is an enlarged detail perspective view of one of the arms or bolts. In all of which views like letters and figures refer to like parts throughout.

45 Referring to the drawings, I will describe the various parts of my invention and their working relation to each other.

In the drawings A. is the outer ring of wood which is the portion of the head that 50 is hooped up solid into the barrel. B. is the central wooden portion of the head and it is the removable portion of the head. To this outer wood ring portion A. is secured a ring of metal C, which may be in one piece 55 or in segments. This metal rim C. is pro-

vided with four or more loops c^1 under which the ends of the arms or bolts catch to bolt the head in. To this central wooden portion B. a projecting ring of metal D. is screwed; this ring may be solid or in segments. It 60 is also provided with four or more loops d^1 which register radially with the loops on the outer metal ring. This metal ring D. is provided on its under side with a recess or projection in which is held a packing ring of 65 cork E. which laps over onto the wood of the outer rim A. and forms an air-tight joint when the bolts are forced out into the loops on the outer rim A.

In the center of the removable head portion B. a base plate G. is let in and screwed fast to the wood, and a central bolt F. standing up in its center passes through the other central parts as follows. This base plate G. is provided with a track g^1 cut out of its 70 flange into which the stop pin h^5 works as the pivot plate H. turns. This pivot plate H. is provided with four projecting pivots, h^1, h^2, h^3, h^4 , on which the ends of the arms I. are pivoted; these arms and pivots may be 75 four or more, as desired. When the arms I. are placed in position on the pivots, the follow plate J. with its series of holes, j^2, j^3, j^4, j^5 , receives the ends of the pivot pins h^1 , etc., and forms a support for the ends of the 80 pivots on the top side of the arms. This follow plate J. is provided with a square projection j^1 for a wrench, by means of which the plates H. and J. may be turned 85 and the bolts or arms I. forced outward from 90 the center and into the outer rim. A nut f^1 on the bolt F. holds the combination together and also holds the arms at any extension that is put on them by use of the large wrench holding the head in firmly and making an 95 air-tight joint all around on the cork packing ring E. It takes but a turn of the nut f^1 to clamp up the whole central combination of parts and hold any expansion given 100 to the arms by the force of the large wrench. The end of the bolt F. is provided with cross kerfs dividing it into four parts, and the nut f^1 is provided with four holes drilled through to the thread so that when 105 the nut f^1 is screwed down solid it may be stopped at a point where the holes in the nut register with one of the kerfs in the bolt and a seal wire K. may be inserted to prevent the contents of the barrel from being tampered with.

Having described the various parts of my invention and their working relation to each other, the manner of operating the device is already plainly shown thereby.

5 I am aware that there are removable churn heads, man-hole covers and removable heads for barrels. I therefore do not desire to cover all removable barrel heads, but

10 What I do claim as new and desire to secure by Letters Patent is—

15 1. A fastener for barrel heads comprising, in combination, an outer ring having locking loops formed thereon, a head having a ring adapted to fit within said outer ring and having loops adapted to register with said loops on said outer ring, a base plate secured centrally of said head and having a central pivot post, a revolute member mounted on said base-plate, said revolute member comprising a pivot plate having a central boss fitted over said pivot-post, and having a plurality of upstanding lugs, an upper plate adapted to fit over said pivot plate and secured to revolve therewith, arms pivoted 20 on said lugs and projecting through said loops on said inner ring, and means for re-

volving said revolute member for projecting said arms into engagement with said loops on said outer ring.

2. A fastener for barrel heads comprising 30 in combination, an outer ring having locking loops formed thereon, a head having a ring adapted to fit within said outer ring having loops adapted to register with said loops on said outer ring, a revolute member pivoted 35 centrally of said head, said revolute member comprising a pivot plate having a plurality of up-standing lugs, an upper plate adapted to fit over said pivot plate and having apertures to receive said upstanding lugs, 40 arms pivoted on said lugs, and projecting through said loops on said inner ring and means for revolving said revolute member for projecting said arms through said loops on said inner ring and into engagement with 45 said loops on said outer ring.

In testimony whereof, I affix my signature in presence of two witnesses.

JOSEPH N. CLOUSE.
